Parker & Sweet Jr.
ATTORNEY.

UNITED STATES PATENT OFFICE.

PATRICK F. WHITE, OF WESTERN PORT, MARYLAND.

SASH-FASTENER.

SPECIFICATION forming part of Letters Patent No. 424,238, dated March 25, 1890.

Application filed January 22, 1890. Serial No. 337,696. (No model.)

To all whom it may concern:

Be it known that I, PATRICK F. WHITE, a citizen of the United States, and a resident of Western Port, in the county of Alleghany and State of Maryland, have invented new and useful Improvements in Sash-Fasteners; and I do hereby declare the following to be a full, clear, and exact description of said invention, reference being had to the accompanying drawings, and to the letters of reference marked thereon, which form a part of this specification.

My present invention relates to improvements in sash-fasteners, and is designed more particularly for use in connection with ear-windows, whereby the sash and shutters of the same may be readily adjusted at suitable heights to attain the desired degree of light or ventilation in the simplest and best possible manner; and my improvements consist, essentially, in the novel details of construction and general arrangement of parts, as will be hereinafter fully described, and specifically designated in the claims.

In the accompanying drawings, Figure 1 represents a front elevation of a sash-fastener embodying my improvements; Fig. 2, a rear view of the same, showing the parts in a locked position; and Fig. 3 a similar view with the parts unlocked and ready for operation.

Similar letters of reference indicate like parts in the several figures of the drawings.

In carrying out my invention a suitable rack-bar A is secured to one side of the frame of the window and is preferably let into the wood-work of the same, so as to be concealed from view. The case or receptacle B is secured to the side of the sash in such manner that the teeth of the pinion C, projecting from the side of the case or receptacle B, engage or mesh with the teeth of the rack-bar A. The upper part of the case B is provided with a circular recess a, opening out to one side, and in which is journaled the pinion C, the teeth of which project slightly over upon one side of the case, as shown.

Directly below the circular recess a and opening into the same is provided an elongated recess b, within which is placed a movable block D, the upper end whereof is provided with V-shaped spurs or projections c, adapted to engage with the teeth of the pinion C to prevent the movement of the same, thus keeping the parts in a locked position. The lower portion of the block D terminates in a cylindrical base d, which passes through a suitable opening in the bottom of the case B, where it is provided with a ring e, as shown.

To one side of the recess b and opening into the same is provided a recess g, having a pivoted lever E arranged therein, the inner end of which engages with a notch h in the side of the block D, to depress the same at will and thus release the spurs or projections c from engagement with the teeth of the pinion C, to permit of its operation within the teeth of the rack-bar A.

Beneath the lever E is secured a suitable spring F, the free end of which engages with the notch h' in the side of the movable block D, to keep the spurs or projections c of the same in contact with the teeth of the pinion.

Upon the outer portion of the case B and to one side thereof is secured a stationary and projecting thumb-piece K, while directly below the same is arranged the thumb-piece K' of the pivoted lever E, the object of which is to provide an easy leverage for the ready manipulation of the parts.

In case it is desired to use my improved mechanism in connection with high windows, I provide a suitable roller m, which is designed to be attached to the lower part of the sash, so that a cord or chain n may be used to draw down the movable block D from contact with the teeth of the pinion C, to insure of the proper operation of the parts.

Having thus described my invention, what I claim as new, and desire to secure by Letters Patent, is—

1. A sash-fastener consisting of the case

or receptacle B, provided with the pinion C, engagement-block D, spring F, lever E, and thumb-pieces K and K', in combination with the rack-bar A, substantially as and for the purpose specified.

2. In a sash-fastener, the movable block D, provided with spurs or projections c, cylindrical base d, having ring e, and notches h h', in combination with the pinion C, lever E,

spring F, and case B, substantially as and for the purpose specified.

In testimony whereof I affix my signature in presence of two subscribing witnesses.

PATRICK F. WHITE. [L. S.]
